(57) **CLAIM**

The ornamental design for a scroll cutting knife, as shown and described.

DESCRIPTION

FIG. 1 is a perspective view of a first embodiment of a scroll cutting knife.

FIG. 2 is a front view of the scroll cutting knife of FIG. 1.

FIG. 3 is a right side view of the scroll cutting knife of FIG. 1 (the left side view is a mirror image of this view).

FIG. 4 is a rear view of the scroll cutting knife of FIG. 1.

FIG. 5 is a top view of the scroll cutting knife of FIG. 1.

FIG. 6 is a bottom view of the scroll cutting knife of FIG. 1.

FIG. 7 is a perspective view of a second embodiment of a scroll cutting knife.

FIG. 8 is a front and a rear view of the scroll cutting knife of FIG. 7.

FIG. 9 is both a left and a right view of the scroll cutting knife of FIG. 7.

FIG. 10 is a top view of the scroll cutting knife of FIG. 7.

FIG. 11 is a bottom view of the scroll cutting knife of FIG. 7.

FIG. 12 is a perspective view of a third embodiment of a scroll cutting knife.

FIG. 13 is a front view of the scroll cutting knife of FIG. 12.

FIG. 14 is a right side view of the scroll cutting knife of FIG. 12 (the left side view is a mirror image of this view).

FIG. 15 is a rear view of the scroll cutting knife of FIG. 12.

FIG. 16 is a top view of the scroll cutting knife of FIG. 12.

FIG. 17 is a bottom view of the scroll cutting knife of FIG. 12.

FIG. 18 is a perspective view of a fourth embodiment of a scroll cutting knife.

FIG. 19 is a front, side, and rear view of the scroll cutting knife of FIG. 18.

FIG. 20 is a top view of the scroll cutting knife of FIG. 18.

FIG. 21 is a bottom view of the scroll cutting knife of FIG. 18.

FIG. 22 is a perspective view of a fifth embodiment of a scroll cutting knife.

FIG. 23 is a front and rear view of the scroll cutting knife of FIG. 22.

FIG. 24 is a right and left view of the scroll cutting knife of FIG. 22.

FIG. 25 is a top view of the scroll cutting knife of FIG. 22.

FIG. 26 is a bottom view of the scroll cutting knife of FIG. 22.

FIG. 27 is a perspective view of a sixth embodiment of a scroll cutting knife.

FIG. 28 is a front, side and rear view of the scroll cutting knife of FIG. 27.

FIG. 29 is a top view of the scroll cutting knife of FIG. 27; and,

FIG. 30 is a bottom view of the scroll cutting knife of FIG. 27.

The broken lines in FIGS. 1, 5-7, 10-12, 16-18, 20-22, 25-27, 29, and 30 are for illustrative purposes only, and form no part of the claimed scroll cutting knife.
